UNITED STATES PATENT OFFICE

EDWARD MALLINCKRODT, JR., OF ST. LOUIS, MISSOURI, ASSIGNOR TO MALLINCKRODT CHEMICAL WORKS, OF ST. LOUIS, MISSOURI, A CORPORATION OF MISSOURI

METHOD OF AND APPARATUS FOR PACKAGING

Application filed June 25, 1926, Serial No. 118,440. Renewed June 3, 1932.

This invention relates broadly to a method of, and apparatus for packaging materials; and with regard to certain more specific features, to a method of, and apparatus for packaging ether or a like perishable material. Among the several objects of the invention may be noted the provision of relatively high-speed, automatic means for packaging ether which is used for anesthesia and other purposes, where all possible deterioration during periods of storage should be prevented; the provision of improved automatic means for packaging ether or the like out of the presence of air or a similar fluid deleterious to the ether or the like, and packaging it in the presence of an inert ambient fluid such as gaseous nitrogen or a like non-deleterious fluid; the provision of improved automatic means for replacing the air found in the packages to be used, by the said inert gas, prior to the packaging process per se; the provision of a means of the class described which requires for its separate elements of construction only inherently rugged members, which can be depended upon to provide continuous and satisfactory service; and the provision of apparatus for carrying out the process described which shall be low in cost and upkeep, and which is simple in operation and in manipulation. Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a plan view of the apparatus showing the top removed and certain parts broken away and shown dotted;

Fig. 2 is a left side elevation showing the left wall and a filling element removed;

Fig. 3 is an enlarged plan view of certain intermittent driving elements shown in Fig. 1, and shows said elements in an alternate driving position;

Fig. 4 is a diagrammatic side elevation of a filling mechanism;

Fig. 5 is an enlarged vertical section of the filling mechanism and drive therefor, taken on line 5—5 of Fig. 7;

Fig. 6 is a lateral section of the filling mechanism, taken on line 6—6 of Fig. 5;

Fig. 7 is a plan view of the filling mechanism;

Fig. 8 is an enlarged fragmentary and sectional view of a loading mechanism taken on line 8—8 of Fig. 1;

Fig. 9 is an enlarged sectional view of a conventional automatic bolt clutch;

Fig. 10 is a fragmentary enlarged vertical section of a capping press, taken on line 10—10 of Fig. 2;

Fig. 11 is a vertical section taken on line 11—11 of Fig. 10;

Fig. 12 is an enlarged vertical section taken on line 12—12 of Fig. 2;

Fig. 13 is a vertical section taken on line 13—13 of Fig. 12;

Fig. 14 is an enlarged vertical section of an ejecting means, taken on line 14—14 of Fig. 1;

Fig. 15 is an enlarged section of a filled and closed package or can;

Fig. 16 is a view similar to Fig. 14 showing modified means for supporting and ejecting a package;

Fig. 17 is a diagrammatic side elevation showing means for operating the ejecting means illustrated in Fig. 16;

Fig. 18 is a fragmentary section of a press head showing a typical crank mechanism;

Figs. 19 and 20 are relative schematic layouts of certain cams; and

Fig. 21 is an enlarged detail of a pivoted joint.

Similar reference characters indicate corresponding parts throughout the several views of the drawings.

5 Construction—in general (Figs. 1 and 2)

Referring now more particularly to Figs. 1 and 2, there is illustrated at P a capping press which is provided with a substantial-
10 ly horizontal table T. The press and the table are mounted on suitable supports 1 and 3.

15 The press P has its main or crank shaft 5 intermittently driven from a drive shaft 7 in a manner to be described. A pinion 11 and a loose driven gear 13 serve as the driving elements between these shafts 5 and 7. A cam shaft C, mounted on extensions 9 of the table T and rearwardly of the press P, is 20 chain driven from a pinion 15 made fast to said loose gear 13. The sprocket 17 on the cam shaft C carries a clutch mechanism 19 whereby it may be connected and disconnected 25 from said cam shaft.

A chambered ring or turret R rotates upon a ground plate supported by the table T, said ring being intermittently moved by means of and from the cam shaft C. This 30 is done by means of a reciprocating ratchet-and-pawl mechanism M.

An air-tight evacuating and charging shoe S is adapted to cooperate with the movable ring R to close the chambers of the ring fluid tight, thereby permitting the replacement of the air in the packages by a gas not deleterious to the material being packaged, which gas in the present embodiment comprises nitrogen and which material comprises ether.

40 The packages in their circular intermittent movement with the ring R are at all times positioned in an atmosphere of inert gas or the equivalent, where no air is present, that is, after they enter the chamber. During 45 said intermittent movement they are repeatedly evacuated and recharged by a gas not deleterious to the material being filled, and finally filled by a filling machine F with the fluid that is being packaged.

50 During said intermittent movement the packages are also provided with a suitable cap by a cap shaping and punching press (intermittently driven and timed from the said shaft 5); are crimped and punched shut at the press P; and are delivered downwardly from the machine after re-passing under the shoe S. During intermittent rest periods of the movable ring R, a plurality of cams on the shaft C are adapted to operate a group G 55 of rocker mechanisms for controlling the elevation of the packages within the pockets in the ring R as they move with and in the ring R.

60 The complete described mechanism is housed in a fluid-tight chamber B which is

adapted to contain nitrogen gas or a like non-deleterious fluid at a suitable pressure.

The chamber B (Figs. 1 and 2)

The chamber B comprises conventional top, 70 bottom, side, and end walls composed of suitable material, and properly braced. The front wall 21 of the chamber is adapted to be removed and is held in place by means of suitable thumb screws 23. A gasket is interposed between the removable front wall 21 and the other elements of the chamber. A gas-tight transparent window 25 is preferably provided in the chamber for viewing the process therein. 80

The said drive shaft 7 of the press P emerges from the chamber B through a stuffing gland 27. On the outside of the chamber this drive shaft is provided with a driving pulley 29 or other suitable source of 85 energy input.

An inlet valve 31 for nitrogen or the like non-deleterious gas is provided at one upper corner of the chamber, and an outlet passage 33 is provided at the opposite lower diagonal corner. 90 The outlet 33 leads to a conventional liquid trap 35 for the purpose of preventing entrance of air through the outlet. In the present embodiment a slight plus pressure of pure nitrogen is introduced into the line connected with the valve 31. Hence when said valve 31 is open, nitrogen flows into the chamber B, and being lighter than air, gradually displaces the air downwardly and out of the chamber from the outlet trap 35. The chamber is sealed when this operation takes place. 100

The press P (Figs. 1, 2, 9, 12, 13 and 18)

The press P comprises the conventional head 37 which supports the rotatable drive 105 shaft 7 and the main shaft 5. The gear 13 is rotatably supported on and with respect to the main shaft 5, and is driven at a substantially constant rate from the pinion 11 mounted fast to said drive shaft 7. The main shaft 5 carries the conventional crank 6 for operating the reciprocating die head 39. As will be hereinafter shown, it is desirable to operate the head 39 to make a complete 110 stroke only once during several revolutions of the gear 13. This is because the pinion or sprocket 15 has a reduced gear ratio with respect to the gear or sprocket 17 driven therefrom. For one revolution (a cycle of 115 operation) of the gear 17 the press should operate to stroke once, and to stroke more quickly than a one to one gear ratio to the sprocket 17 would otherwise permit, that is, in view of the relatively slower movements required of the other parts of the machine. 120

In order to accomplish the intermittent stroking operation of the press P, an automatic bolt clutch is used. Clutches of this class are not new per se but a description 130

thereof is here given, in order to clarify the operation of the machine.

Automatic bolt clutch for the press P (Figs. 1, 2 and 9)

5 The clutch comprises a disc 41 keyed to the main or crank shaft 5 and is rotatable therewith. A recess or pocket 43 in this disc 41 permits a bolt 45 to spring into and engage 10 against one side of said recess. The bolt 45 is located slidably in the gear 13 and is securely locked back by a radially sliding dog 47. When not locked in place, the bolt 45 is adapted to be sprung inwardly by means 15 of a suitable spring 49. The dog 47 is adapted to be drawn downwardly against a spring 48 by a lug or dog 53 on a knife cam 51. This normally permits the bolt 45 which is actuated by said rearward spring 49, to spring forwardly until it enters said pocket or recess 20 43. This results in the crank shaft 5 being driven from the gear 13.

The knife cam 51 carries said portion or dog 53 thereon, adapted to draw down the dog 25 47, and also has a barrel camming portion 57 thereon adapted to push the bolt from the pocket in the disc. The action is such that when the knife cam 51 is lowered, then the dog 47 is pulled down by means of the portion 30 53, permitting the bolt 45 to enter the pocket. At this time the camming portion 57 of the knife cam 51 is inoperative to return the bolt 45. However as soon as the knife cam 51 is permitted to rise under the action 35 of a return spring 58, then the portion 57 is effective to cam the bolt 45 out of the recess 43, while the portion 53 is in such position as to permit the dog 47 to re-engage the bolt to hold said bolt out of engagement with the 40 recess.

The knife cam 51 is made to descend at predetermined intervals by the motion of a cam 59 mounted fast on the cam shaft C, which cam C transmits its motion through a 45 linkage 61, 63 connected with the knife cam 51. The result is that for each revolution of the cam shaft C, the press clutch is engaged once, that is, for a number of revolutions of the gear 13 depending upon the speed ratio 50 between it and the cam shaft C. This ratio is of the order of four to one in the present embodiment. This means that the press operates quickly with respect to the other operations and only once in several revolutions 55 of the gears 13 and 15. Furthermore its operation is specifically timed with regard to the operation of the cam shaft C, which is driven by the constantly moving sprockets 15, 17 and the chain 65 therebetween. The clutch thus 60 remains engaged for one revolution of the crank shaft 5 of the press P, this being one out of every four revolutions of the gear 13.

The clutch 19 (see Fig. 1), which intermittently connects the sprocket 17 with the cam shaft C, is exactly analogous to the clutch

above described, but instead of being automatically operable from a cam shaft, is manually operable from a suitable linkage L which passes from the chamber B by way of a stuffing gland 67 where it is primarily operable from a suitable foot pedal 69. By means of the clutch 19, the operation of the parts driven from the cam shaft C may be started and stopped manually from the outside of the chamber. As long as the pedal 69 is held in its depressed condition, the machine 75 operates continuously.

Carrier ring R (Figs. 1, 2, 8 and 10 to 12)

Mounted on the table T is a stationary supporting ring 71 which is held in place by a plurality of bushings 73. The bushings 73 also act as push rod guides in a manner to be described. The ring 71 has an upper ground surface 75 which is adapted to flatly receive the lower ground surface 77 of the said carrier ring R which lies on said ring 71. The carrier ring R is rotatably borne on a central vertical pin 79 held to the table T. The surfaces of the two rings R and 71 make 80 a gas-tight contact and are oiled. The ring R is rotatably movable with respect to the ring or plate 71. The ring R is provided in its peripheral rim with a plurality of vertically arranged pockets 81 which are adapted 85 to slidably receive the packages which are to be filled. Each pocket 81 is provided with a sidewardly extending passage 83 which leads to an upper flat ground surface 85 of said ring R. An outer flange 87 of said ring R is 90 provided with a plurality of recesses or notches 99 for purposes to be described.

Ratchet and pawl mechanism M (Figs. 1, 2 and 3)

The mechanism M is adapted to intermittently drive the ring R in a counter-clockwise manner (Fig. 1) from the cam shaft C. The amount that the ring R is intermittently driven is such as to have each pocket 81 take 105 up the position of the pocket just ahead of it at each intermittent movement.

In order to do this there is provided on the cam shaft a uni-lobed cam 89 which is adapted to drive a follower 91 slidably held in 110 guides 93. The follower 91 is tangentially arranged with respect to the ring R, and is normally retracted against the cam 89 by means of a return spring 95.

A holding pawl 97 normally engages one 120 of a plurality of notches 99 cut into the periphery of the ring R and prevents movement of said ring in either direction. A driving pawl 101 is pivotally held to the follower 91 and is adapted to engage the notches 99 to 125 drive the ring R only when the follower 91 moves to the right (Fig. 3). Upon retraction of the follower 91 by the spring 95, the pawl 101 is adapted to disengage from its respective notch 99. An overrunning lug 103

is held to the follower 91 and is adapted to engage a heel 105 of said pawl 97. This pawl is pivoted on a pin 104 and is normally held against a stop 106 by spring 108. When the 5 follower 91 is driven to the right, whereby the pawl 101 drives the ring R, then the lug 103 engages the heel 105 just as the pawl 101 is about to sink into its notch 99. The pawl 103 is held in position by the stop 106 as it 10 reacts on the heel 105. This frees the ring R for movement under action of the cam 89. Upon return of the follower 91 the pawl 101 (spring pressed into its notch 99 by a leaf 15 spring 100) automatically leaves its notch 99, while the pawl 97 does not leave the respective notch into which it has automatically slipped, because the lug 103 overruns the heel 105, pivoting on its own axis against the light reaction of spring 108 which reaction is less than that of spring 107. The lug 103 is spring pressed against a stop as illustrated. The pawl 97 is normally and automatically held in engagement with a notch 99 by a spring 107. It is evident from the 20 above, that for every revolution of the cam shaft C, that the ring R is advanced one notch, that is, each pocket 81 takes up the position which the next respective pocket had. During those periods when the ring R 25 does not move, it is positively held in alignment by the pawl 97.

Evacuating shoe S (Figs. 1, 2 and 8)

The purpose of the shoe S is to hold each 30 pocket 81 in a fluid tight condition in five of the positions thereof, as moved by the ratchet and pawl mechanism M, and also to cooperate in the replacement of the air normally found in the packages, by the inert or non-deleterious gas such as nitrogen used in the present embodiment. Four of these positions are those which are had immediately after the 35 unfilled package is delivered to each respective pocket 81, and the fifth position is the one had at the last position of the said pocket in the cyclic operation of the ring R, that is, just prior to the delivery of the filled and closed package from the machine. The first 40 four positions above mentioned are designated in Fig. 1 by the letters U, V, W, X. The fifth one is designated by the letter Z. Position U starts a cycle of operations and position Z ends the cycle.

The shoe S comprises an arcuate sector 45 plate 109 (Fig. 8) which has a lower flat ground surface 111 adapted to engage a portion of the upper flat ground surface of the ring R. The plate 109 rests of its own weight on the ring R but is guided into position by pins in bushings 114 fastened to bracket 113 (Fig. 2). If desired, springs 50 may be added to press the shoe S against the ring R. Bracket 113 is supported by the central pin 79 and by the outer supports 115 as 55 illustrated. The shoe S is provided with an

opening 117 adapted to align with one of the pockets 81 which is under the shoe S when the ring R is in its stationary position and said pocket is in its position U. This opening 117 has a cylindrical delivery chute 119 70 connected therewith for the purpose of delivering packages N down to and through said opening 117 by gravity. The chute 119 extends upwardly and out through the top of the chamber B through a suitable gas-tight opening. This chute is provided with a flexible section 118 for permitting the shoe S to rest in a gas-tight position on the ring R. The interior of the chute 119 is normally filled with the air of the outside atmosphere. Packages are delivered to the chute 119, one 75 on top of the other, by a conventional delivery system 121, located outside of the chamber B.

The shoe S is also provided with preferably three openings A, E and O (Figs. 1 and 2) which are positioned to align with the passages 83 leading to the pockets 81 when three of said pockets 81 are in their positions V, W and X. Evacuating lines 147, 149 and 151 are connected to the openings A, E and O respectively. These lines pass upwardly and out of the chamber B by means of suitable gas-tight openings and pass to suitable evacuating apparatus (not shown). Alternately 80 spaced to the openings A, E and O, the shoe S is provided with nitrogen filling openings H and I. These openings H and I are positioned to align with the passages 83 leading to the pockets 81 when two of said pockets 81 85 are in positions substantially midway between their positions V, W, and W, X, respectively. The openings H, I, are more or less elongated for reasons to be made clear, and are in communication with the inside atmosphere of the chamber B at all times. 160

From the above, it is evident that each pocket 81, as it passes with its package, from a position out from under the opening 117 is adapted to be substantially evacuated at its position V; to be charged with nitrogen from the atmosphere within the chamber B at a position or positions midway between positions V and W; to be re-evacuated at position W; to be refilled with nitrogen from said nitrogen atmosphere at a position or positions midway between positions W and X; to be evacuated a third time at its position X and to be finally refilled with nitrogen when it passes from under the shoe S. This means that any open container or package positioned within the pocket 81 will have substantially nothing but nitrogen in it when it appears open in the chamber B. The openings H, I, are elongated because the pockets 81 do not come to rest at the mid-position, but move. Hence, more time is given for filling by the slot formation.

The above described repeating process for evacuating and refilling with nitrogen gives

a substantially air free and purely nitrogen gas filled package within each pocket 81 as it emerges from the shoe S. This is because the very slight amount of air left in the 5 pocket 81 and package after the first evacuation is greatly diluted by the next inlet charge of nitrogen at the mid-position H. The second evacuation will leave an equivalently very slight amount of air and nitrogen 10 mixture, the greater part of which is nitrogen. The second charge of nitrogen again dilutes this already much diluted mixture. The third evacuation rids the pocket and package of substantially all air. 15 Finally the last charge of nitrogen (obtained when the pocket passes from beneath the shoe S) leaves nothing but nitrogen (or other inert gas) in the pocket 81 and open package therein. The number of repetitions which might be employed is only limited 20 by the length of the shoe S. It is to be understood that the herein described process is to include evacuating packages and refilling them with any fluid which is non-deleterious to the particular material being 25 packaged, whatever the material may be.

Delivery mechanism for evacuating shoe (Figs. 1, 2 and 8)

30 This mechanism comprises two oppositely arranged slideable fingers 123, arranged to partially intersect said opening 117 in the shoe S. These fingers pass through gas-tight stuffing glands. One of them has a 35 driving link 125 suitably attached thereto, and the other has a rocker arm 127 attached thereto. A pivoted rocker arm 129 bears at one end against the barreled face of a combination cam 131 on the cam shaft C. 40 The barreled face of the cam 131 is unlobed. The other end of the rocker arm 129 is slidably and pivotally connected at 132 with the said member 125 and carries a roller 133 adapted to engage said rocker arm 127 (see Figs. 1 and 21). The arm 129 is 45 normally held in engagement with the cam 131 by return spring 132. Whenever the lobe of the cam 131 engages the rocker arm 129, then the fingers 123 are caused to withdraw from their position at the bottom of the stack of containers or cans N in the chute 119, thus releasing the cans.

To lower the cans gradually, a follower push rod 135 is provided to be slidably borne 50 in the proper respective bushing 73. This rod is normally either weighted or spring-pressed downwardly. Its lower ball end 137 engages the outer lifting end of the rocker 139. The other end of the rocker 139 comprises a follower which engages a cam 141 55 on the cam shaft C (see Fig. 19). The cam 141 is so timed with regard to the said cam 131, that as the said holding fingers 123 are retracted from the passage 117 then the rod 135 is in position to receive the lowermost

can on the upper end thereof. The cam 141 is so shaped that thereafter the rod 135 is caused to descend and to gently deposit the lowermost can on the ground surface 75 until the next pocket 81 is in position to receive a can or package. It may be noted from the drawings that the type of package used, is one having a neck and a flared and flanged opening at the top, adapted to receive a lead or other suitable cover in said 75 flange. This means that an annular space 143 is left between cans within the chute 119, whereby return of the fingers 123 is facilitated.

Fig. 12 shows a rod similar to the rod 135 80 equipped with an anti-friction ball end 137, and an upper spring-pressed buffer 145 for the purpose of lightly contacting with the cans N.

The package filler (Figs. 1 and 4 to 7) 85

The illustration of the filling mechanism has been omitted from Fig. 2 in order to clarify the structure of parts behind it, but it is clearly shown in the above-named views. 90 This filling mechanism is novel per se as well as the packaging device as a whole. It provides an accurate charge for each can, and comprises among other features, a manual adjustment to compensate for the expansion 95 under change of temperature of the fluid being delivered.

This filling mechanism F comprises a fluid-tight box 153 suitably supported above the table T and containing a liquid having a 100 lever Q. The liquid is to be filled into the packages N, it being ether in the present embodiment. The ether flows steadily into the box 153 from an inlet 155 and passes from an overflow 157. An axle 159 supported laterally of the box 153 rotatably carries 105 two spaced plates 161. These plates 161 are provided with cross pins 163 for rotatably supporting a plurality of dippers 165. The dippers 165 have a pouring edge 167 and an 110 inlet edge 169. Their construction is such that the centers of gravity are directly below the respective pins 163, when the lips or edges 167 are vertically positioned, that is, when the dippers are not re-positioned by 115 other elements to be described. Outside of one of the plates 161, each rotatable axle 163 is provided with a depending crank 171 carrying a roller 173 at the end thereof.

Normally the dippers 165 are permitted 120 to hang substantially vertically from their axles 163, and as they dip into the charge of fluid, these dippers are filled (the plates 161 rotating counter-clockwise, Fig. 5, by means of mechanism to be described).

A delivery trough 175 is mounted within the box 153 and is adapted to carry fluid out through the bottom of said box to a point centrally above the position of rest for the pockets 81 as they emerge from the shoe S. 130

Therefore, in order to empty the dippers into the trough 175, there is provided a stationary cam 177 adapted to engage the followers 173 as the dippers move to a point above said trough 175. By this means each dipper is rotated and caused to spill its charge into the trough, and as the roller 173 leaves the cam 177, the respective dipper takes up its original substantially vertical position under the action of gravity. A suitable buffer 179 is provided for preventing excessive oscillations of the dippers as they return to their normal vertical positions.

In order to adjust the amount (volume) of fluid that each dipper will pick up there is provided a gauging track or cam 181. This is swung from a rotatable support 183 hung from said shaft 159, and is supported by an adjustable slide clamp 185. The clamp 185 is operable to be tightened and loosened from a wheel 186 at the outside of the chamber B, as illustrated in the drawings (Fig. 1). In order to regulate the position of the cam 181, after it is unclamped, there is provided therewith a connecting rod 187, to which is pinned a crank 189 held to a control shaft 191. The control shaft 191 also passes from the chamber B and carries a wheel or the like suitable for making adjustments. This wheel is designated by the numeral 192 in Fig. 1. The crank 189 is used to reset the position of the cam 181.

The cam 181 is adapted by a given particular position, to regulate the positions at which the dippers 165 emerge from the fluid. This is because the followers 173 cooperate with the edge 193 of the cam 181. The changeable positions of the dippers are proportional to the change in position of the cam, and the amount (volume) that each dipper will hold depends upon this positioning. This is evident when it is noted that the level in each dipper depends upon the relative level of the lip 169 with respect to the dipper. By the above means a predetermined weight is always deliverable from each dipper.

Filler driving mechanism (Figs. 1, 2, 4, 6 and 7)

In the present embodiment eight dippers are used. Outside of the box 153, on the shaft 159, is provided an eight lobed ratchet 195, adapted to drive the shaft and the plates 161 in a counter-clockwise direction (Fig. 4). Since each revolution of the cam shaft C results in advancing the ring R one notch, thereby advancing a package to be filled beneath the snout 197 of the trough or spout 175, it is desirable to empty one of the dippers 165 into said trough to fill said package.

In order to accomplish the above purpose the said cam 181 is provided with a peripheral lobe 199 adapted to oscillate a bell-crank lever 201. A connecting rod 203 links the

bell-crank lever 201 with a rocker arm 205 rotatably supported on the shaft 159 of the filler. The rocker arm 205 carries a pawl 207 adapted to engage the notches of the ratchet 195, and to drive said ratchet ahead one notch for each revolution of the cam shaft C. By this means one filling charge is delivered from the trough 175 for every revolution of the cam shaft C, and for each placement of a can N under the snout 197. 75

Package positioning means for the filler F (Figs. 1, 2 and 5)

In order that the can or package N may be brought well up in connection with the snout 197, there is provided a rocker 209 similar to said rocker 139 for the can delivering means. The rocker 209 cooperates with a cam 211 on the cam shaft C and is adapted to drive a follower rod 213 similar to said rod 135 in connection with the delivery mechanism. The rod 213 is adapted to raise each can up into cooperation with the snout 197 as the ring R comes to rest, and when the ring R moves, the rod 213 descends into its respective bushing 73 and below the surface 75, thereby permitting the can N to be replaced on the surface 75. Further movement of the ring R takes the can on to its next position after it has been permitted to descend. The timing of the cam 211 is such that the snout 197 and said can N are in connection during the filling period (see also Fig. 19).

The capping press K (Figs. 1, 2, 10 and 11) 100

The press K is mounted on the table T and is driven in a one to one ratio by the chain drive 215 from the crank shaft 5 of the press P. In other words, the press K quickly makes one cyclic action for each time that the press P does so.

Press K comprises a bolster plate 217 having an opening 219 therein adapted to receive a strip of lead tape 221. This bolster plate 217 overhangs the ring R. The tape 221 unrolls from a roll 223 from one side of the machine, passes through the bolster plate 217 and is drawn out on the other side by means of a conventional feeder 225. This feeder 225 draws tape through the press and feeds it out to the side of the table T in the chamber B. This is done by means of a universal linkage 227, which is driven from the crank shaft 229 of the press K. The feeder 225 is not new per se, and its action is well known in the art of presses and the like. The feed of the tape 221 is intermittent because the action of the press K is intermittent. An intermittent ratchet on the feeder 225, operable on the up stroke of the press, is effective to draw the tape out by increments.

The ram 231 of the press K, driven by a conventional crank 236 (similar to crank 6 shown in Fig. 18) on the shaft 229, Fig. 1, is provided with two punches 233 and 235.

The punch 233 (Fig. 10) is adapted to punch a bulge 237 into the tape against a head 239 held in a portion of the bolster plate 217 below the opening 219. Upon the next movement of the press, the die 235 punches the bulge portion 237 out of the tape and down into the upper flanged end of an awaiting can N. For each movement of the press the tape moves so as to move a bulge 237 from 10 the head 239 over to a point under the die 235, and to bring a new portion of the tape over the head 239 to be bulged.

Can positioning mechanism for the press K (Figs. 1, 2 and 10)

This mechanism comprises a rocker 241 similar to the said rocker 139 adapted to cooperate with and be driven to oscillate by a cam 243 on the cam shaft C. Its other end 20 cooperates with a lifting rod 245 similar to the rod 135, but positioned directly under the punch 235 of the press K. The cam 243 is timed so that as the ring R comes to rest bringing a filled can under the press K, the 25 rod 245 is caused to lift the can to a position such that its flared head may be grasped and accurately centered by two slides 247 (Fig. 11). The slides are shown closed in around the flared nozzle as the ram of the press K 30 descends. Two camming spurs 249 projecting downwardly from the ram, positioned in a plane at right angles to the plane of the punches 233, 235, are adapted to push the slides inwardly around said flared nozzle as 35 the punches descend to do their work of bulging, punching, and delivering the punched and bulged cap into the nozzle of the can N. When the punches recede the slides 247 also 40 recede from the head of the can under action of a pair of springs 251.

The cam 243 is so shaped that as the slides 45 247 recede, the rod 245 descends to a position in its respective bushing 73 below the surface 75, thus replacing the can N in the ring R. Three positions of the filled can are shown in Fig. 10, namely, its filled, uncapped position, its raised position wherein a cap is being applied, and its position 50 after application of the cap. It now remains to crimp the flanges of the flared head down over the edges of the cap. The bulge is put into each cap for convenience in punching it open.

The press P (Figs. 1, 2, 12 and 13)

From the press K, the capped and filled cans are moved by increments to the first of a pair of positions J, D, under the said press P. The press P has a bolster plate 251 which overhangs the ring R and is provided, with a plurality of openings 253 aligning with two of the pockets 81 when the pockets are positioned under the press. The bolster plate 251 slidably carries a pair of die plates 255 normally held in open position by a pair

of springs 257 but driven to a closed position by a pair of spurs 259 fastened to a punch head 261 held to the ram 39.

At each revolution of the cam shaft C, a pair of cans N is raised from the ring R by 70 linkages to be described into the openings 253, with their nozzles in position to be grasped and aligned by the split dies or plates 255. At this juncture the ram 39 is caused to descend. The punch head 261 carries a crimping punch 262 and a closing punch 263 therewith. These punches engage corresponding recesses cut in the dies 255 when the latter are in said closed position.

It is evident from the above, that after the cans N are raised, the die block 261 descends to close the plates 255 around the flared heads of the cans N, and at the same time to inwardly crimp the flange of the right hand can (Fig. 12) and to flatten the inwardly crimped flange of the left hand can. By this means one can is prepared for the final closing operation and the other is finally closed. As the die recedes, the plates 255 spread apart and permit the cans to descend by means of the linkages to be presently described. The ring R is stationary during these operations. Its increments of advance are such as to move a crimped can from its right hand depressed position (Fig. 12) to 85 its left hand depressed position in one revolution of the cam shaft C.

Mechanisms for lifting the cans at the press P (Figs. 1, 2 and 12)

These mechanisms comprise a pair of rocker arms 265 similar to the said arm 139, which cooperate with a pair of cams 267 on the cam shaft C. The rockers 265 move in unison and are adapted to drive a pair of rods 269 preferably aligned with the punches 261, 263. The cams 267 are timed so that the cans N are lifted from their positions under the press P after the ring R comes to rest. Said cams are so shaped that the rods 265 remain in their upward positions while the press P operates on the cans N, and after the plates 255 are opened, said rods 269 gently descend to replace the cans N on the surface 75. The rods 269 then take up positions below the said surface 75. The rockers 265 and 213 are mounted between the legs of the support 1.

Package ejecting means (Figs. 1, 2 and 14)

From position D, the cans N move successively by increments to the position Z, under the shoe S. The position Z is one in which the respective pockets 81 are aligned with a lower opening 268 of like diameter in the table T and the plate or ring 71 (see Fig. 14). The outlet delivery pipe 269 is screwed into the plate 71 at the opening 268 and clears the table T (Fig. 14). As the cans move into the position Z, they are dropped

from positions in the ring R into said outlet delivery pipe 269. The pipe 269 leads downwardly and outwardly from the casing B, and thence to a take-off belt 273.

It may be noted that as the pockets 81 pass in under the shoe S, they are cut out of communication with the nitrogen atmosphere in the chamber B. Hence when the pockets coming in communication with the air filled pipe 269, no air can leak into the apparatus. The pocket 81 is the only portion that becomes filled with air and this is the portion which is evacuated when the next air-filled can N is received from the air-filled delivery tube 219.

Complete operation

The chamber B is closed and sealed. The valve 31 is opened in order to permit inlet of the nitrogen or the like, which forces air out through the outlet trap 35. Ether or the like is permitted to flow into the filler F through the inlet 155. The overflow 157 for the filler maintains the level of liquid therein. Other liquid leveling devices might be employed. The delivery mechanism 121 and the take-off mechanism 273 is put into motion.

The shaft 7 is assumed to be rotating, and hence the gears 11, 13, 15 and 17 are rotating and pipe 119 is assumed to contain cans. In order to start the filling machine proper, pedal 69 is manipulated to close the clutch 19. For approximately every four revolutions of the gears 13, 15, the cam shaft C rotates once. Hence the clutch on the press P is automatically closed once in about four revolutions of the gear 13. This is done from the cam 59. Consequently the press K also operates once for about every four revolutions of the gear 13. It is to be understood that the particular gear ratio between gears 15, 17 may be varied to suit particular conditions. Presses P and K operate once for every revolution of the cam shaft C.

The closure of the clutch 19 results in the intermittent movement of the ring R and delivery of the cans N (one by one) to the pockets 81 in said ring. The intermittent movement of the ring is accomplished by means of the ratchet mechanism M, and the delivery of the can N by movement of the fingers 123 and rod 135 (Figs. 3 and 8). The mechanism M is operated from the cam 89 and the fingers 123 from the cam 131. The rocker 139 is being operated from the cam 141 to gently place the cans, one by one, on the surface 75.

After each can N is positioned in a pocket 81, it is first intermittently moved to positions V, W and X, and thus thrice evacuated and alternately twice filled with nitrogen. After the last evacuation, the next or fourth intermittent movement of the ring R carries the can N out from under the shoe S to auto-

matically fill with, and remain in, an atmosphere of nitrogen.

At this juncture the rocker 209 lifts the can in order that it may be filled at the filler F, and replaces it on the surface 75 after filling. The rocker 209 is operated from the cam 211. The cam 199 serves to cause one bucket 165 to spill its contents into the trough 175, each time that a can is brought up to the snout 197 of said trough 175.

About three movements of the ring R bring the filled can up into a position beneath the press K, where the rocker 241 is caused to lift the can up into the press K where it is provided with its loose cap. The rocker 241 lowers the can into the ring R. Said rocker is operated from the cam 243.

About 11 movements of the ring R bring the can to the position J under the press P. At this point, the right hand rocker 265 (Fig. 12) lifts the can up into a position where the crimping die 262 is effective thereon, after which the rocker permits the can to descend. Another movement of the ring R brings the can into its position D under the press P. Then the left-hand rocker (Fig. 12) is effective to lift the can into a position where the closing die 263 is effective thereon, after which the rocker permits the can to descend. It is evident that the period of time occupied by the operation of the punch head 261 is only a fraction of the total period of the time that the cans are under the press P. This is because of the gear ratio between the sprockets 15, 17.

Next, about three movements of the ring R are occupied in bringing the can from its position D to its position Z under the shoe S, where it is dropped from the machine. One more movement of the ring R brings the empty chamber 81 from the position Z to the position U where it is again loaded.

It is evident from the above, that each revolution of the cam shaft C results in a can being brought up to each event, whereat a particular operation is performed upon it. The action is entirely automatic and continuous.

The machine may be stopped at any time by removing pressure from the pedal 69.

To recapitulate shortly, upon depressing clutch pedal 69, shaft C begins to rotate, immediately advancing ring R the space of one pocket by means of cam 89 and ratchet mechanism M. Ring R, now being at rest, an empty can N is lowered from pipe 119 by a rocker arm and other rocker arms raise cans N to proper places under filler F, capper K and main closing press P and hold them there for the respective operations of filling, capping and closing, which are properly synchronized by means of the cams on cam shaft C.

Between the pipe 119 and the filling position under filler F, it will be understood that

each can is connected with the vacuum and fills with nitrogen from the surrounding atmosphere in the chamber. This takes place three times, that is, in positions V, W and X.

5 The finished cans finally reach the drop-out pipe 269.

It is evident from the above that the ether which is filled into the cans N is never in contact with the air, either during or after

10 packaging. By this means the ether is kept from absorbing air, which is a contributing factor to the deterioration in packaged ether.

The automatic process provides a positive enlarged output of neat air-free packages of

15 ether. If desired, a ring of solder may be applied to the closed heads after delivery from the described machine. It is to be understood that the ether or the like is supplied to the inlet line 155 in an air free and other-

20 wise pure condition. It may be put into such a condition by the means described in my United States Patents Numbered 1,461,539 and 1,508,563.

It is evident that the gas chamber B, prop- 25 er, comprises all of the space included within the walls of said chamber, except the pas-

119 and 269, which for the present purposes 30 will be classified with space not within the gas chamber proper. This is because the

chamber B might be shaped to dispense with these chutes, as such, without violating the principles of construction claimed herein to be new and novel. The chamber B provides

35 means for maintaining an artificial atmosphere or volume of ambient fluid about and in the packages to be filled. Any ambient fluid, not deleterious to the material being

40 packaged, may be used.

Modified can support (Figs. 16 and 17)

It has been found desirable under certain conditions, to carry the cans N in the pockets 81 without allowing them to rest on the 45 surface 75. In order to do this, spring-

pressed plungers 277 are caused to partially intersect the pockets 81, at or near the bottoms thereof. The cans rest on these plungers (Fig. 16) as said cans travel with the ring 50 R, instead of on the ground surface 75.

In order to eject the cans through the outlet opening 268, a spring retracted plunger 279, held in the shoe S over the opening 268, is adapted to push the cans out past the resili- 55 ently held plungers 277, that is, as the cans come to rest over said outlet 268. The linkage for depressing the plunger 279 is illus-

trated in Fig. 17, and comprises a simple rocker arm 281 adapted to intermittently de- 60 press the plunger 279, as the successive cans N come to rest thereunder. The rocker arm 281 is actuated by a cam 283 added to the cam shaft C, properly shaped and timed.

It is evident that various substitutions may 65 be made for the plungers 277, for resiliently

supporting the cans N, such as spring fingers or the like.

Conclusion

As hereinbefore indicated, the ambient 70 fluid to be used in this machine is to be construed broadly as comprising a fluid which is non-deleterious to the material being packed, whatever the material may be. Such an ambient fluid may comprise an inert fluid, an 75 oxygen-free fluid or any other type which will be included by the term non-deleterious, in view of the particular material adapted to be packaged. The term "non-deleterious" is used broadly to include all fluids having a 80 chemical or anesthetic action beneficial or supplementary to the therapeutic effect of the ether.

The term "filling" is to be construed as meaning the insertion of material, regardless 85 of whether it actually fills the package or not.

The term "ether" includes commercially pure ether and chemically pure ether.

In view of the above, it will be seen that 90 the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense. 100

I claim:

1. Apparatus for packaging, comprising means for substantially evacuating a package, means for delivering it to a chamber filled with a fluid, non-deleterious to the 105 material being packaged, means within the chamber for filling, capping and ejecting the package, and means for intermittently moving said package to said recited means in sequence.

2. Apparatus for packaging comprising means for passing packages into a fluid-filled chamber which has no free oxygen therein, means for alternately evacuating said packages as they pass into said chamber, means for recharging them with said fluid from said chamber as they pass in, means within the chamber for filling, capping and ejecting the package, and means for intermittently moving said package to said recited means 110 in sequence.

3. Apparatus for packaging automatically, comprising a chamber having no free oxygen therein, means for substantially evacuating a package, delivering it to said chamber without admitting air, means for intermittently moving the package to filling, capping and ejecting means within the chamber without admitting air, said recited means being automatically coordinated. 125

4. Apparatus for packaging comprising a chamber filled with a fluid which is non-deleterious to the material being packaged, means for substantially evacuating an open package, means for delivering said package to the chamber without admitting air, and intermittently moving the package to filling, capping and ejecting means, and controlling means adapted to effect operation of said 10 recited means in sequence.
5. Apparatus for packaging automatically, comprising a chamber filled with a fluid, which is non-deleterious to the material being packaged, means for alternately evacuating and recharging packages with fluid from said chamber, means for passing said packages into the chamber as they are alternately evacuated and recharged, and means for filling, closing and ejecting said packages from the chamber. 15
6. Apparatus for packaging automatically, comprising a chamber filled with a fluid, means for alternately evacuating and recharging packages with fluid from said 20 chamber, means for passing said packages into the chamber as they are alternately evacuated and recharged, and means for closing the packages within said chamber, and controlling means adapted to effect operation 25 of said recited means in sequence.
7. Apparatus for packaging ether comprising means for successively evacuating a package and alternately refilling it with a non-deleterious gas moving from an atmosphere 30 of said gas, means for passing said packages into said gas, and means for filling, capping and closing said packages while in said last-named atmosphere, and controlling means adapted to effect operation of said recited 35 means in sequence.
8. Apparatus for automatically packaging ether comprising means for maintaining an atmosphere of non-deleterious gas, means for moving packages into said atmosphere 40 comprising a chambered movable member, means for delivering packages to the chambers of the member to be moved therewith, means for successively evacuating, means for alternately recharging the chambers of the 45 member with gas from said atmosphere when the packages are placed therein, means for filling and means for closing said packages as said member carries them into said atmosphere from the evacuating and recharging 50 means.
9. Apparatus for automatically packaging ether comprising means for maintaining an atmosphere of non-deleterious gas, means for moving packages into said atmosphere 55 from the outside atmosphere comprising a movable member having a gas-tight connection with the surface upon which it rests said surface being within the means for maintaining said atmosphere, the member being 60 formed with pockets adapted to receive the packages, a stationary shoe having a gas-tight connection with a portion of one surface of said member and openings therethrough adapted to permit communication between the pockets and the said outside atmosphere during a portion of the movement of said member to permit ingress of a package, means for alternately evacuating the chambers when out of communication with said both atmospheres, means for filling and means for closing them while in communication with the atmosphere of gas, said packages passing into said atmosphere of gas by passing from under said shoe. 65
10. Apparatus for automatically packaging ether comprising means for maintaining an artificial atmosphere, means for successively moving packages into said atmosphere, comprising a rotatable member, the member being formed with pockets adapted to receive packages, means for repeatedly cutting the pockets out of communication with said atmosphere, means for evacuating said pockets while so cut off, means for filling and means for closing the packages while the pockets are in communication with the artificial atmosphere. 70
11. Apparatus for automatically packaging ether comprising means for maintaining an artificial atmosphere, means for successively moving packages into said atmosphere, comprising a rotatable member, the member being formed with pockets adapted to receive packages, means for repeatedly cutting the pockets out of communication with said atmosphere, means for evacuating the pockets while so cut off, means for filling and means for closing the packages while the pockets are in communication with the artificial atmosphere and means for delivering packages 75 to and removing them from said member. 80
12. Apparatus for automatically packaging ether comprising means for maintaining an artificial atmosphere, means for successively moving packages into said atmosphere, comprising a rotatable member, the member being formed with pockets adapted to receive packages, means for repeatedly cutting the pockets out of communication with said atmosphere, means for evacuating the pockets while so cut off, means for filling and means for closing the packages while the pockets are in communication with the artificial atmosphere, means for delivering packages to and means for removing them from said member, included in said cutting-off means, for taking packages out of communication with said artificial atmosphere. 85
13. In apparatus for packaging ether automatically, a chamber adapted to have an artificial atmosphere maintained therein, a movable member therein, the member being formed with pockets adapted to receive packages, means for admitting packages to said pockets, means for evacuating said packages 90

- and means for preventing inlet of the outside atmosphere to said chamber, means for filling and means for closing the packages while in said chamber, and means for ejecting them from said chamber without admitting the outside atmosphere.
14. In apparatus for packaging ether automatically, a chamber adapted to have an artificial atmosphere maintained therein, a movable member therein, the member being formed with pockets adapted to receive packages, means for admitting packages to said pockets, means for evacuating said packages and means for preventing inlet of the outside atmosphere to said chamber, means for filling and means for closing the packages while in said chamber and pockets, and means for ejecting them from said chamber without admitting the outside atmosphere.
15. In apparatus for packaging ether automatically, a chamber adapted to be filled with nitrogen, an intermittently movable member therein adapted to move packages within the chamber, means for admitting packages to said member, means for evacuating the packages and means for preventing inlet of the outside atmosphere to said chamber, means for maintaining oxygen-free ether in the chamber, means for filling the ether into the packages while they are positioned in said chamber, means for closing said packages while therein, and means for delivering the packages from the chamber without admitting outside atmosphere.
16. Apparatus for packaging ether comprising, an enclosing chamber, means for maintaining an atmosphere of nitrogen therein, a movable member therein, means for delivering packages to said movable member and means for evacuating them without admitting air to the chamber, means within the chamber for moving said member, means therein cooperating with the movable member to fill the packages with ether, means therein cooperating with said movable member for capping the packages, means therein for cooperating with the movable member to close the caps on the packages, and means therein for delivering filled and closed packages from the chamber without admitting air.
17. In apparatus for automatically packaging, means for delivering packages to a gaseous chamber without admitting air comprising a movable member in the chamber, said member having pockets therein adapted to receive packages, means for maintaining a substantial vacuum, and means for successively communicating said pockets with the outside air, the vacuum and the gas in said chamber.
18. Apparatus for automatically packaging ether comprising means for maintaining an atmosphere of non-deleterious gas, means for moving packages into said atmosphere from the outside atmosphere comprising a movable member having a gas-tight connection with the lower surface upon which it rests, said surface being within the means for maintaining said atmosphere, the member being formed with pockets adapted to receive the packages, a stationary shoe engaging the movable member to effect communication between the pockets and the said outside atmosphere during a portion of the movement of said member to effect ingress of packages, said shoe communicating with means for alternately causing evacuating of the pockets when out of communication with said both atmospheres and for permitting communication with the atmosphere of gas, means for filling and means for closing them while in communication with the atmosphere of gas and means for preventing the packages from seating on said surface.
19. Apparatus for automatically packaging ether comprising means for maintaining an atmosphere of non-deleterious gas, means for moving packages into said atmosphere from the outside atmosphere comprising a movable member having a gas-tight connection with the surface upon which it rests, said surface being within the means for maintaining said atmosphere, the member being formed with pockets adapted to receive the packages, a stationary shoe engaging the movable member to permit communication between the pockets and the said outside atmosphere during a portion of the movement of said member to effect ingress of packages, said shoe communicating with means for alternately causing evacuating of the pockets when out of communication with said both atmospheres and means for permitting communication with the atmosphere of gas, means for filling and means for closing them while in communication with the atmosphere of gas, means for preventing the packages from seating on said surface and means for delivering them from said inside atmosphere.
20. In an apparatus for packaging materials in an atmosphere of non-deleterious gas and out of contact with air, means for introducing exhausted open containers into a chamber filled with such gas, comprising a movable member in said chamber sliding between upper and lower fixed surfaces and having gas tight engagement therewith, means for moving such member and bringing it to rest at predetermined stations, pockets for the reception of a container in such movable member, a passageway for the delivery of containers leading from outside the chamber through one of said fixed surfaces and registering with a pocket at one of said stations, said movable member having apertures connected with each pocket and registering at a later station with a passage through one of said fixed members leading to an exhausting device, said upper fixed surface being

thereafter cut away so as to expose the container to the atmosphere of the chamber and permit operations thereon at still later stations.

5 21. In apparatus in accordance with claim 20, a plurality of exhausting devices registering with said apertures at successive stations and means therebetween for admitting gas from the chamber to said pockets.

10 22. In apparatus in accordance with claim 20, a portion of said upper fixed surface making gas tight engagement with said movable member in the vicinity of the last station, and a passageway for the discharge of containers leading from outside the chamber through one of said fixed surfaces and registering with a pocket at said last station.

15 23. In apparatus for packaging materials in an atmosphere of non-deleterious gas and out of contact with air, a chamber adapted to be filled with such gas, and means for removing filled and capped containers from said chamber, comprising a movable member sliding between upper and lower fixed surfaces and making gas tight engagement therewith, said movable member being formed with pockets for holding containers, a passage-way for the discharge of containers leading from outside said chamber through one of said fixed surfaces, and means for moving said movable member and bringing it to rest with a pocket in registration with such discharge passage.

20 24. In apparatus for packaging materials a chamber adapted to be filled with gas, a rotating turret in said chamber, said turret having a plurality of pockets therein for the reception of containers, means for rotating said turret and bringing it to rest at predetermined stations, means for continuously supplying a container to each pocket at one of said stations without access of air to the chamber, means for exhausting such container and pocket at a succeeding station; means for filling said container at a later station; means for capping said container at a still later station; and means for discharging said container from its pocket without access of air to the chamber at a still later station.

25 25. The method of packaging chemicals in an atmosphere of gas which is non-deleterious to the chemical to be packaged and in the absence of air, which comprises subjecting a progressively advance line of containers to the following treatment, each step being carried out simultaneously upon one of the containers in the line; exhausting the open container, introducing the open exhausted container into an atmosphere of said gas without substantial admission of air, filling the container with the chemical to be packaged in said gaseous atmosphere, and capping each container in said gaseous atmosphere.

30 26. The method according to claim 25,

adding the step of removing the container from said gaseous atmosphere.

27. The method according to claim 24, in which the steps of exhausting the open container and introducing the open exhausted containers into an atmosphere of said gas are repeated a plurality of times.

28. The method according to claim 25, in which the chemical to be packaged is ether.

In testimony whereof, I have signed my name to this specification this 23rd day of June, 1926.

EDWARD MALLINCKRODT, JR.
